UNITED STATES PATENT OFFICE.

BENJAMIN F. MIESSNER, OF NEW YORK, N. Y., ASSIGNOR, BY MESNE ASSIGNMENTS, TO THE MAGNAVOX COMPANY, OF SAN FRANCISCO, CALIFORNIA, A CORPORATION OF ARIZONA.

TELEPHONE TRANSMITTER.

Application filed March 12, 1919. Serial No. 282,155.

To all whom it may concern:

Be it known that I, BENJAMIN F. MIESSNER, a citizen of the United States, residing at New York city, in the county of New York and State of New York, have invented certain new and useful Improvements in Telephone Transmitters, fully described and represented in the following specification and the accompanying drawings, forming a part of the same.

The invention was suggested by the necessity for telephoning in or from airplanes, where the noise of the engines interferes seriously with the operation of ordinary telephone transmitters, and by observation of the entire or partial failure of methods and devices intended to overcome this difficulty.

The invention therefore comprises a method and means for substantially eliminating objectionable noises which are present in an airplane or other noisy places, while properly transmitting desired sounds, usually the human voice.

Stated in more general terms, the object of the invention is to accomplish the clear and satisfactory telephonic transmission of certain sounds with the substantial elimination of other sounds.

In general terms the method of accomplishing this object consists in causing the sound-responsive element, such as a diaphragm, to respond to sound vibrations from a source relatively near and substantially opposite one face of the diaphragm, and causing it to be substantially unresponsive to sound vibrations proceeding from sources relatively distant, wherever located, or those from a source relatively nearly in line with the plane of the diaphragm, whether near or distant from the diaphragm.

More particularly stated, the method consists in causing or permitting sound vibrations which it is desired to transmit, and which may therefore be identified as "desired" sounds, to impress themselves effectively on one side of the diaphragm so that the resulting vibrations of the diaphragm may be converted into electrical vibrations for transmission, while causing or permitting sound vibrations which are not desired for transmission, and may be identified as "undesired" sounds, to exert equalizing or neutralizing effects on the two sides of the diaphragm so that the diaphragm is in effect

substantially inert or unresponsive to such sound. Still more particularly the method consists in permitting equalizing access to the diaphragm of sounds of the second class from any relatively distant source and any direction, and in some cases positioning the plane of the diaphragm to produce or increase an equalizing effect with respect to sounds proceeding from certain sources, whether near or distant.

In general terms, the apparatus for accomplishing the desired object consists in a diaphragm exposed on both sides to contact by air pressure variations caused by sound vibrations and substantially balanced with respect to undesired sounds, while unbalanced with respect to desired sounds, and also substantially balanced with respect to sounds proceeding from directions approximately in line with its plane, without regard to their classification as desired or undesired sound; and suitable co-operating means for converting the vibrations of the diaphragm into electrical vibrations for transmission.

The operative principle of my invention is such, as more particularly explained hereinafter, that when sounds of different characters proceed from a point located at any given distance from a face of the diaphragm, such distance being substantially greater than the distance at which a sound source is to be placed with the purpose of reproduction, the extent to which the diaphragm is unaffected (or in other words, the degree to which elimination of such sounds is effected) depends upon the rate of pressure variation in the different sound waves; and factors which determine this rate include pitch, amplitude, and specific wave form.

The accompanying drawings comprise certain diagrams to graphically explain the theory involved and also show certain forms of apparatus embodying the invention. The method forming a part of the invention is carried out in connection with these or other forms of apparatus. After studying the drawings in connection with this specification, persons skilled in the art will understand that the method and the apparatus are subject to reasonable variations within the spirit of the invention, and I do not limit myself to details except as claimed. In the drawings:—

Fig. 1 is a view showing in a convention- 110

alized way a telephone transmitter of common form in a certain position in relation to sound waves also represented conventionally;

5 Fig. 2 shows the same transmitter in another position;

Fig. 3 is a conventionalized showing of a novel diaphragm arrangement;

10 Fig. 4 is a diagram, showing the device of Fig. 3 in a different relation to sound waves.

Fig. 4^a shows the same device in another arrangement in relation to sound waves;

15 Fig. 5 is a diagram illustrating the effect of a sound wave of a certain sort on a certain diaphragm;

Fig. 6 is a diagram showing the effect of a different sort of sound;

Fig. 7 is a diagram showing the action of still another sort of sound;

20 Fig. 8 is a diagram illustrating the effect of "sound shadow";

Fig. 9 is a sectional view of a typical simple magneto transmitter embodying my invention;

25 Fig. 10 is a view with certain parts in section and certain parts in elevation of a transmitter of the carbon button type embodying my invention in one form,

Fig. 11 is a rear elevation of the same 30 with the rear casing removed;

Fig. 12 is a section of the structure of Fig. 10 with the rear casing removed;

35 Fig. 13 is a sectional view of a simplified carbon transmitter embodying my invention; and

Fig. 14 is a front elevation of the same;

Fig. 15 is a vertical section of a modified form of transmitter.

40 Fig. 16 is a transverse section of the same. The development of a method and apparatus for producing the desired result followed a theoretical study of the nature of sound vibrations in relation to means for telephonic reproduction of them, and orderly 45 experiments directed by such theoretical study. A clear understanding of the inventive problem and the solution for it provided by the invention will be facilitated by a brief theoretical discussion based upon the study referred to:

Under ideal conditions sound proceeds from a source in the form of an enlarging sphere in which at any point the sound acts upon a responsive medium by reason of 55 variations or oscillations in air pressure, and it is these pressure variations, which might be described as definite pressure impacts (in some cases negative as well as positive), which cause the movement of the responsive 60 medium, such as a telephone transmitter diaphragm. The wave front form defined by a circle whose center is the sound source, will evidently have a different curvature in comparison with any definite datum at different distances from the source, so that for

descriptive purposes the wave front form may be said to be relatively sharply curved near the source and relatively straight or flat at points far removed from the source. Thus, considering a datum dimension of 70 about 3 inches, representing the diameter of a telephone diaphragm, the wave front form of a sound reaching it from a distance of 3 or 4 inches is sharply curved or convex, and the front form of one reaching it from 75 only about 3 feet or a greater distance is evidently practically flat to all intents and purposes.

Sound vibrations differ in their characteristics in ways which can most easily be expressed by graphical representation. Taking only two examples: a curve representing graphically the cross-section of the ideal sound sphere above mentioned in one of the planes of the source, for a sound of one 85 character will show a sharply peaked form, representing sudden and intense variations in air pressure, while the curve of another sound will show an easy curvature or a substantially sinusoidal form. Differences in 90 characteristics represented by such curves may be referred to a time factor since in the sharply peaked curves the pressure variations of whatever degree are relatively compressed and pass a given point in a brief 95 time while the variations represented by the "easy" curves are relatively extended and require relatively much more time to pass a given point. Sounds of the same intensity and pitch may have very different characteristics represented by peaked curves, or sinusoidal ones or almost anything between the two.

100 In a telephone transmitter as ordinarily arranged (Figs. 1 and 2) a diaphragm *d* forms substantially the flat side of a closed hemisphere of which the spherical part is the casing *c*. Wherever this transmitter is placed with relation to a sound source, air pressure variations are impressed upon all 105 parts of its surface and become effective upon the flexible diaphragm by bending it in and out as shown graphically in Figs. 1 and 2. The depression of the diaphragm (Fig. 1) is caused by positive external air 110 pressure, and the bulging or outward curve (Fig. 2) is caused by a negative pressure or one below the pressure of the air within the casing. Figs. 1 and 2 show the diaphragm arranged in different positions with 115 respect to the parallel lines which represent the approximately straight wave front form of sounds coming from a considerable distance, and whose relative proximity to each other indicates the relative intensity of pressure. It is shown graphically in these figures that the diaphragm responds to the pressure variations regardless whether its plane is parallel to the sound wave front 120 or in any other position. Such a diaphragm 125

will respond to the sound of the voice proceeding from a point opposite to it and from a distance of only 2 or 3 inches, and it will also respond to any sound of sufficient intensity proceeding from any direction and from any distance. There is no selective capacity and any considerable extraneous sounds are transmitted along with the desired sound which is usually that of the speaking voice.

Various means for excluding undesired sounds have been proposed in order to make it possible to use a telephone transmitter in noisy places. These devices have failed partially or entirely to give the desired results for reasons understood by persons skilled in this art.

My theoretical study above referred to, and study of the practical difficulties involved in telephonic transmission under difficult conditions, as for example, in an airplane in proximity to very noisy internal combustion engines, led me to experiment with a diaphragm supported in a relatively thin ring r shown graphically in Fig. 3, and open to free access of air pressure variations on both sides. It was discovered that such a diaphragm would vibrate only when the influencing sound waves possessed certain characteristics of direction, curvature, frequency and wave form, and that it will not respond to vibrations advancing in the direction of its plane, as shown in Fig. 3, because as clearly indicated there, equal and oppositely directed pressures are produced on its two sides. When waves advance in directions approximately perpendicular to the plane of the diaphragm, it is found that their effect depends chiefly upon the wave-front form and other characteristics of the waves and the thickness of the supporting ring; or, otherwise stated, the effect depends upon distance of the source and the rate of wave-pressure variation, with due regard to ring-thickness.

Sounds desired for reproduction, to which the diaphragm must therefore respond accurately, are usually those of the human voice, and will usually proceed from the lips, held opposite and within two or three inches of the diaphragm, or even closer, as indicated in Fig. 4, in which s represents a sound source located as above, and the curved lines concentric with the source represent the relatively sharply-curved front-form of the sound waves, any given pressure zone of which, as is obvious from this diagram, strikes the front of the diaphragm and produces the corresponding diaphragm movement, before the same pressure zone can reach, and affect, the rear surface. A concurrent cause of diaphragm response, and prevention of equalization by such sounds as are now in consideration, is indicated diagrammatically in Fig. 8, which shows

that a large part of the sound waves are reflected back, away from the diaphragm without opportunity to reach and affect the rear surface thereof, and also that what may be called a "sound-shadow" effect is produced at the rear of the diaphragm, which tends to prevent equalization, and to produce proper diaphragm response.

As the sound source s is moved farther away from the diaphragm, the front curvature of the sound waves reaching the diaphragm decreases; that is, the wave front becomes flatter in relation to any given linear dimension, such as the diameter of the diaphragm. When the sound source is three feet or more from a diaphragm of about three inches in diameter, the wave front form at the diaphragm is, to all intents and purposes, flat, as indicated in Figure 4^a. This flattening of the wave front reduces the responsiveness of the diaphragm to the sound vibrations, and conversely produces an equalizing effect upon the two sides of the diaphragm when the ring r is of suitable thinness, until at a certain distance which may be only two, three or four feet for a great variety of sounds of moderate intensity, the diaphragm is practically unresponsive to their vibrations. This equalizing action due to the flattening of the wave front can best be understood by considering an ideal representation of the cross-sectional form of a certain sound wave, as shown in Fig. 6. Here the elevation of different points of the curve c above the base line b indicate the degree of pressure at that point of the curve. When the ring r is of moderate thickness t in relation to the diameter of the diaphragm d , it is apparent that with a substantially flat wave front the pressure upon the front face of the diaphragm at any instant is substantially balanced by an almost identical pressure on the back of the diaphragm. This equalization is also graphically indicated in Fig. 4^a, in which the parallel lines represent the wave front form, which is substantially straight, as shown, when the sound source is considerably distant from the diaphragm, and the relative proximity of these lines indicates the degree of pressure. This equalization is not primarily dependent upon reduction in loudness of the sound as the source is moved farther from the diaphragm, but upon the relative straightening of the wave front, as above explained. Thus, sounds received from sources two or three feet from a face of the diaphragm will fail to vibrate the diaphragm appreciably in many cases when a sound of otherwise similar character proceeding from a source much nearer the diaphragm, say two or three inches, and no louder at that point than the other sound, will cause ample vibration, as indicated in Fig. 4.

When a diaphragm supported and arranged as above described is employed with suitable means for converting its vibrations into electrical impulses, as shown and described hereafter, in certain telephone transmitters embodying the invention, the voice of a person speaking into the transmitter in the normal way is correctly transmitted for reproduction, and a great variety of other sounds, if they are being produced in the vicinity, and which would ordinarily affect the transmitter and interfere with the clear transmission of the desired sounds, are eliminated, for the reasons above explained.

For example, if these undesired sounds are the voices of other persons talking in the vicinity, even when such persons are located substantially opposite the diaphragm of the instrument at either front or back, and only two or three feet distant, the sound of their voices is largely or entirely eliminated. Many other sounds from similarly located sources are also eliminated. When sounds have certain characteristics, as later explained, which make their elimination especially difficult, and when these difficulties are so great that the phenomenon of flattening of their wave front form in relation to the diaphragm is not sufficient to produce an equalizing effect upon the diaphragm to eliminate such sounds, complete elimination may be accomplished by turning the instrument so that the plane of the diaphragm is more or less in line with the sound source, as previously explained.

The completeness of elimination of any sound, with its source at any given distance more than, say, three feet, from a face of the diaphragm, depends upon various characteristics of that sound, such as pitch, amplitude or loudness, and other factors, as sufficiently explained in greater detail hereafter, and after considering such detailed explanation of different characteristics and their effect upon diaphragm structures of my invention, it will be found that the degree to which elimination of different sounds, at any given distance from a face of the diaphragm, is effected, depends upon the rate of pressure variation in the different sound waves.

A sound wave having a very pronounced "peak" formation, when proceeding from a source opposite to the diaphragm, and even when the source is a considerable distance away from the diaphragm, say five or six feet, may produce a sudden pressure on the front of the diaphragm before its speed of advancement has carried it to the other side and effected neutralization; and this may happen in spite of the fact that the wave front form in such a case is substantially flat, which would be sufficient to cause neutralization in the case of a sound of less intense pressure variation. This may occur, for instance, when the wave length is comparatively short in proportion to the thickness of the ring. This is shown graphically in Fig. 5 where w is the curve indicating variation in pressure due to the sound vibration, b is the base line of neutral or atmospheric pressure, l is one-half of a wave length, and p is a point in the pressure curve parallel with the front of the diaphragm. The sound wave is supposed to strike the diaphragm substantially at the center so that in the selected example the pressure point p is supposed to be applied to the center of the diaphragm, but for greater convenience in applying reference characters the curve is shown at one side of the diaphragm. The vertically arranged numerical ordinates indicate comparative pressures both positive and negative. The point p^1 designates a pressure point in the curve which has passed the diaphragm. The dimension t indicates the thickness of the ring which is small in relation to the diameter of the diaphragm. The dimension $2t$ indicates a distance of travel of the sound wave equal to twice the thickness of the ring, and this is the horizontal dimension between the front of the diaphragm and the point p^1 of the curve. Evidently the point p^1 before its effective pressure can be exerted upon the back of the diaphragm must have travelled a distance equal to t in the direction of the arrow and an equal distance back again before it can become effective on the back of the diaphragm. The net effective pressure upon the face of the diaphragm at the moment indicated in the diagram is therefore the difference between the pressure at p and that at p^1 which, by consulting the numerical ordinates, is seen to be 8; that is, a positive sharp pressure impulse of an intensity equal to 8 in a total positive pressure range of 10 is impressed upon the diaphragm. The foregoing makes it clear that the thickness of the ring has an important effect upon response of the diaphragm to sounds represented by a curve of the sort shown in Fig. 5, for evidently if the ring is thicker the part of the curve to the rear of the diaphragm may be of a negative pressure value, for example, and in this case, the pressure effect upon the face of the diaphragm will be much greater than the maximum sound value properly attributable to the sound curve in question. Also taking the same sort of curve or one which is even more compressed or with more sharply accentuated pressure peaks, it can easily be understood that with a ring of increased thickness which dimension is not in conformity with the wave length of the sound in question, it is readily possible for the pressure variations impressed upon the two

sides of the diaphragm to be thrown entirely out of phase so that an entirely false vibration will be set up in the diaphragm.

It is therefore evident that, to eliminate 5 sounds of the character just described, the ring r should be made as thin as is practicable. When the ring is so designed, substantial equalization is effected, according to the principles above explained, even by 10 sounds having sharply-peaked curves described, within ranges of pitch and intensity usually encountered, when the sounds proceed from sources approximately opposite, and sufficiently distant from the diaphragm 15 so that the wave front form at the diaphragm is substantially flat.

A sound vibration of the character represented by the curve w , Fig. 5, may be one which it is desired to reproduce, and in that 20 case when the sound proceeds from a source such as the mouth of a speaker held opposite the diaphragm and near it, the sound will evidently be responded to correctly by the diaphragm because of the sharply 25 curved front formation of the sound waves when proceeding from a distance which, in the assumed case, is usually no greater than the diameter of the diaphragm and because of the concurrent sound shadow effect produced 30 behind the diaphragm with respect to sounds proceeding from a point close to its front, as graphically shown in Fig. 8.

But the same curve may also be representative of an undesired sound proceeding 35 from a greater distance, and from a point more or less nearly opposite a face of the diaphragm. In that case, the flattening of the sound source to a greater distance, tends to 40 cause equalization, and the distance at which equalization will be effected for a sound of the characteristics described depends to a certain extent upon the sharpness of the sound curve, or in other words, upon the 45 rate of sound pressure variation. With certain sounds having a short wave length with rapid pressure variation, equalization is facilitated, as explained in connection with Fig. 5, by making the ring r as thin as reasonably possible. This emphasizes the importance of the time factor, or time-and-distance factor briefly mentioned above, since sounds of the character mentioned even 50 when proceeding from a considerable distance and from a point nearly opposite the diaphragm would cause it to respond if the ring were of sufficient thickness to prevent pressure exerted upon one side from being approximately equalized by the same pressure value reaching the other side without appreciable delay.

When a sound has very rapid pressure variations, making its elimination correspondingly difficult, although the response of the diaphragm to such sound is proportionately

reduced as the diaphragm is removed from the source (while maintaining the plane of the diaphragm approximately perpendicular to the direction of the source), a substantially complete elimination of such a sound might not be possible without removing the instrument to an impracticably great distance. In such cases, responsiveness of the instrument to the sound may be entirely eliminated, even with the instrument in 75 close proximity to the sound source, by positioning it so that the plane of the diaphragm is approximately in line with the direction of the source, as previously explained. 80

If the wave curve is of less pronounced form, such as a sinusoidal form shown in Fig. 6, where the wave is long in proportion to the thickness of the ring r , it will be evident that as the wave advances upon the diaphragm it will not produce any appreciable response because the pressures upon both sides of the diaphragm become practically equalized with unappreciable delay. In other words, such a sound has a capacity 90 to relatively easily effect equalization of a diaphragm arranged according to my invention, and equalization of the diaphragm in respect to such sounds occurs when the diaphragm is removed only a relatively 95 short distance from their source, even when the source is directly opposite a face of the diaphragm.

A sound represented by such a curve may be one of the voice sounds desired for transmission, proceeding from a source substantially opposite and near the diaphragm. In that case equalization is undesirable, and is prevented by the sharply curved wave front formation due to the proximity of the sound source, or otherwise explained by the sound shadow effect exemplified in Fig. 8. 100

Another case requiring consideration is one in which a sound is of a character represented by a curve having a relatively short wave length and a smooth or sinusoidal curve as shown in Fig. 7. It would theoretically be possible to secure a pressure impulse greater than the maximum pressure in the wave, unless ring r is quite thin. In this case the negative pressure at p'' added to the positive pressure at p' is evidently considerably greater than the true maximum positive or negative wave pressure of the curve indicated by P . Therefore, in this 110 case, with a relatively thick ring the sound proceeding from a considerable distance and having a fairly flat formation would in some cases not equalize the pressures upon the diaphragm properly for eliminating the sound. In an extreme case of this sort it 115 is possible for the maximum negative pressure effect to be applied to one side of the diaphragm at the moment when the maximum positive pressure is applied to the other 120 125 130

6 side. This would, when converted into an electrical vibration and reproduced, have the effect of substantially doubling the true intensity of the sound. In the case of voice 10 sounds this and similar phenomena would also often distort the sound and result in indistinct or faulty reproduction.

In actual practice the telephone diaphragm does not respond appreciably to vibrations above 5000 per second. This corresponds to a wave length of about 2 inches. If a wave be of sinusoidal form the half wave or pressure zone would be 1 inch long. If the ring r were $\frac{1}{4}$ inch thick, 2^t in Fig. 15 7 would equal $\frac{1}{2}$ inch or $\frac{1}{2}$ of the wave length. The case just assumed represents, therefore, probably the worst condition that is to be met with (considering ideal, or simple, wave 20 forms), and to meet this difficulty without positioning the diaphragm angularly with relation to the undesired sound in question, the ring should be made thinner, and in this case the difficulty would be avoided.

If a given supporting ring cannot be made 25 thin enough to entirely eliminate the difficult sound conditions such as just described, within structural limitations, the difficulty may be met in that case partially or entirely by angular positioning of the diaphragm.

With regard to all characters of sounds proceeding from any distance from 2 or 3 inches up to many feet (with reference to 35 a diaphragm of about a three inch diameter) and from points more or less nearly in line with the plane of the diaphragm, equalization is effected as shown graphically in Fig. 3, by the fact that the pressure variations of all such sounds reaching the diaphragm from such directions are equalized on the two sides of the diaphragm with sufficient promptness by permitting the vibrations to reach both sides of the diaphragm with substantial freedom.

40 The discussion of sound sources and the movement and character of sound waves has been based on simple and ideal forms, and the curves given represent such ideal forms. Actually the question is complicated by the 45 inherently complex nature of most sounds, and by sound reflections, and other phenomena. But I am convinced by my study that all complications may be reduced for the purposes of this invention to a combination 50 of the simple problems enunciated, and I find that the method and apparatus here disclosed will act under all ordinary conditions to substantially solve the problem propounded, for practical purposes.

60 Fig. 9 shows a simple magneto transmitter modified and adapted to embody my invention. The diaphragm D is held in a relatively thin ring R which may of course for convenience in assembling consist of 65 separate parts, namely, a rear member 1

and a front member 2 secured together in any convenient way. Attached to the rear part 1 of the ring is a frame or spider consisting of two or more arms 3 which carry the magnet frame 5 and magnets 6, which 70 are as usual. The front of the diaphragm D may be entirely unobstructed except for the very slight marginal overlap of the ring member 2, and the rear face is substantially unobstructed since free access of air over a large area of the rear face is afforded by the skeleton or open construction of the frame 3. The freedom of access of vibrations to the rear of the diaphragm may be increased when it is considered desirable by making 75 the magnet-windings 6 relatively short and placing them toward the rear so that the pole-pieces 6^a extend considerably from the front of the magnet windings. The relatively insignificant area of these pole-pieces 80 adjacent to the diaphragm does not obstruct the latter in respect to sound vibrations to any appreciable extent. Otherwise, when a certain amount of obstruction of the rear of the diaphragm is caused by the presence of magnets or other parts, this effect may be counterbalanced or neutralized if desired by providing a shield or screen 2^a which in Fig. 9 is in effect an inward extension of the outer flange of the ring 2, and this may have a 85 central aperture 2^b designed to more or less closely equal the exposed rear area of the diaphragm for balancing effect. In this way air pressure variations caused by sound vibrations are permitted to reach both sides 90 of the diaphragm with sufficient freedom to produce substantial equalization and to eliminate undesired sounds, while desired sounds impressed upon the front of the diaphragm from a point a few inches distant would be properly responded to by the diaphragm without equalization, these effects causing the diaphragm constructed and arranged as shown in Fig. 9 to respond 95 to vibrations of the different characters substantially as previously explained in connection with the conventionally shown diaphragm of Figs. 3 to 8. The vibratory responses of the diaphragm to the desired sounds are converted into electrical impulses 100 for transmission by magnetic induction in the usual way, and since undesired sounds are not responded to by the diaphragm for the reasons explained, they will not be converted into electrical impulses or transmitted.

105 The method constituting one principal part of my invention may, therefore, be carried out in one exemplifying way in connection with the apparatus shown in Fig. 9, 110 and the method so performed is heretofore described in sufficient detail to enable it to be understood and is also specified hereafter in certain claims.

115 The method may also evidently be carried 120

out in connection with other forms of the apparatus described hereafter.

Figs. 10 to 12 show a typical carbon button transmitter modified and adapted to embody my invention. The diaphragm D^1 is carried in an insulating packing 7. This in turn is carried in a recess 8 in ring 9 which is quite thin in relation to the diameter of the diaphragm. A frame or yoke 10 is screwed to the back of ring 9. Damping devices comprising springs 14 are secured to the frame 10, or to the ring 9, and exert pressure against the rear face of the diaphragm through insulating pads 15. The frame 10 supports the variable carbon resistance device, which comprises as usual a cup-like receptacle 16, a back disk 17, a granular filling 18, and a button 19, the reduced central portion of which passes through a mica diaphragm 20. The button 19 is connected to diaphragm D^1 by a stem 21 and suitable securing devices. Binding posts 22 and other electrical connections are provided as usual.

Mainly for mechanical protection of the parts and for convenience in supporting the instrument a rear casing or housing 25 is provided. This is secured in any convenient way to the ring 9 and may preferably be provided with a lug or ear 26 bored for connection to a suitable standard. The casing 25 is provided with a multiplicity of holes 27 to permit sufficiently free access of air pressure variations to the interior of the casing and so to the back of the diaphragm.

The front of the diaphragm might be entirely exposed except for the slight overlap of flange 28 of ring 9, but in an arrangement preferred in some cases, as in Fig. 10, this flange may be continued inward to provide a covering or screen 29 for the front of the diaphragm. Such front covering or screen, however provided, will be formed to permit the necessary free access of sound vibrations to the diaphragm, as by being provided with a multiplicity of holes 30. The number and arrangement and total area of the apertures in the front cover and the rear casing when these are employed may be proportioned to each other with sufficient accuracy to permit sufficiently free access of sound vibrations to both sides of the diaphragm to bring about the desired unresponsiveness of the diaphragm to certain sound vibrations, that is, those proceeding from a source relatively distant from the diaphragm or which are in the plane of the diaphragm, while leaving it fully responsive to vibrations from a source relatively near and substantially opposite the face of the diaphragm, such as words spoken to the transmitter in the usual way; this for the reasons previously explained.

Evidently in some cases the rear casing may be omitted and a support for the in-

strument may be provided at the central member of frame 10 or otherwise, and the front cover or screen 29 may also be omitted when desirable.

A carbon button transmitter comprising only the parts described above may in some cases respond to sound vibrations having access to the rear of the diaphragm sufficiently to cause more or less disturbance. That is, such vibrations of the button itself will transmit sounds additional to those impressed upon the diaphragm or will neutralize the action of the diaphragm to some extent. To provide against this difficulty I provide means for insulating the carbon button from sound vibrations so that it is responsive only to the mechanical vibrations transmitted to it from the diaphragm. Fig. 12 shows one arrangement for this purpose in which a cylindrical housing 31 is screwed upon the front end of cup 16 forming a continuation of the carbon resistance supporting device. This housing contains an internal flange 32 provided with a central aperture fitting the stem 21 very closely but yet with sufficient clearance to avoid interfering with the reciprocations of the stem. This flange substantially prevents passage of air to and from the chamber within it so that air pressure variations are substantially prevented from having access to the button. Other means for excluding air and air pressure variations may also be provided, as for example, a rubber disk 33, cemented or otherwise secured to the front face of housing 31 and secured at its center to the stem 21 by suitable holding devices.

Figs. 13 and 14 show a carbon transmitter of simpler form modified and adapted to embody my invention. The frame comprises an annulus 35 against the front edge of which the diaphragm D^2 is clamped by a flanged ring 37, having spring-fingers 36 engaging annulus 35. The frame also comprises a center-piece 38 to which insulating pieces 39 and a carbon disk 40 are secured in any usual or convenient way. The frame also comprises two or a small number of arms 41 connecting the center-piece with the annulus 35. These arms provide very wide and free spaces through which air pressure variations may reach the back of the diaphragm. The ring 37 may somewhat overlap the front edge of the diaphragm in order to hold it in position, but is usually provided with a large central opening 42, or in some cases may be provided with a center-piece 43 connected to the outer portion of the ring by arms 44, and the center-piece may be provided with perforations 45. The diaphragm D^2 as shown lies close to the disk 40 and bears against carbon pellets or granules 46 in the recesses 47 of the disk as usual in transmitters of this type. The sufficiently free access of sound vibrations to both sides

of the diaphragm afforded by the arrangement shown causes or permits, for the reasons heretofore considered, the desired equalization of vibration effects upon the two sides 5 for the purpose of eliminating, substantially or wholly, sounds from a source relatively distant from the diaphragm or which is in the plane of the diaphragm, the diaphragm being, however, effectively responsive to 10 sound vibrations from a relatively near source and advancing transversely thereto.

A modified transmitter of the carbon-but-
ton type is shown in Figs. 15 and 16. This
structure is an exemplification of one ar-
rangement of the diaphragm and its casing
15 to permit very complete balancing of the
diaphragm and to avoid interference with
the diaphragm action which may be caused
in other arrangements by sound reflections
20 and sound shadows, due to proximity of
other parts of the instrument.

The casing 50 encloses in a chamber 51 a variable resistance device 52 of the carbon-button type. This resistance unit 52 is of similar construction to that of Figs. 10 to 12, except that the cap 31^a serves merely to retain diaphragm 20 and other parts of the resistance unit in assembly, and is not formed to enclose the outer end of the button 19. A sleeve 53 is connected to casing 50 and extends from it a considerable distance. The outer end of this sleeve is flared out to provide the rear member 54 of a housing for the main diaphragm D^s. The diaphragm housing is completed by another member 55 having an internal screw thread 56 engaging the threaded periphery of member 54. The diaphragm is held between the members 54 and 55 in a suitable insulator 56. A stem 57 is firmly secured to the center of the diaphragm D^s, and passes through the central bore of sleeve 53. The diameter of this bore is only slightly larger than the diameter of stem 57, so that sound vibrations are substantially entirely excluded from the interior of casing 50, and at the same time the longitudinal vibratory movement of stem 57 is not impeded. At its rear end, stem 57 has a screw thread 58 entering a threaded socket in the outward end of button 19. After the diaphragm is put in position with the stem 57 extending through the bore of sleeve 53, the carbon-button unit 52 is placed in chamber 51 and the button is screwed upon the rear end of stem 57 by rotating the unit, a screwdriver slot 59 being provided in the rear face of the button unit for that purpose. After adjustment, the unit 52 is locked against rotation or end movement by a set screw 60 passing through the casing 50, and the rear end of the casing is closed by a cap 59^a.

This transmitter may be conveniently

supported, as, for instance, on a telephone desk standard of ordinary construction, the upper end of which is indicated in dotted lines at 65, by providing the casing 50 with an ear 66, adapted to fit in the clevis usually provided on such a standard, and having a bolt hole 67 to receive the usual clamping bolt. 65 70

The housing members 54 and 55 opposite both faces of the diaphragm D⁸, are provided with apertures 61 of suitable area and number, and as is readily understood from Fig. 15, the arrangement of parts is such that these apertures may be made of substantially the same effective area at both sides of the diaphragm, so that equalization of air pressure variations on the two sides of the diaphragm may be made as complete as is desirable for the purposes hereinbefore indicated. There is no large body near the rear of the diaphragm to interfere with the described arrangement of apertures in the diaphragm casing, the cross-sectional area of the stem 53 being practically negligible in this respect, and the length of the hollow stem is such that the diaphragm is removed far enough from the carbon-button housing 50 so that the housing does not impede or reflect sound vibrations sufficiently to interfere with the desired equalization of the main diaphragm to any appreciable extent. 75 80 85 90

What is claimed is:

1. In a telephone transmitter, the combination of a casing having a tubular extension of small diameter, a diaphragm housing at the end of said extension, a diaphragm therein, a variable-resistance device in said casing, and a stem located movably and fitting closely in the bore of said extension and connecting said diaphragm with said resistance device, said diaphragm housing having apertures affording free and substantially equal access of air-pressure variations to both sides of the diaphragm. 100 105

2. In a telephone transmitter, the combination of a support, a casing hinged thereto, a carbon resistance device in the casing, 110 a tubular extension on the casing, a relatively narrow housing on the outer end of the extension, a diaphragm in the housing and a connection between the diaphragm and the resistance element extending through the 115 tubular extension, said housing being apertured at both sides to afford substantially equal access of air pressure variations to both sides of the diaphragm.

In testimony whereof I have hereunto set my hand in the presence of two subscribing witnesses. 120

BENJAMIN F. MIESSNER.
